DISPENSING TANK FOR A FLOOR TREATING MACHINE OR SIMILAR ARTICLE

Paul E. Gaudry, Laval des Rapides, Quebec, Canada, assignor to Electrolux Corporation, Old Greenwich, Conn., a corporation of Connecticut

Filed Nov. 17, 1967, Ser. No. 9,455

Term of patent 14 years

Int. Cl. D15—07

U.S. Cl. D49—17

FIG. 1   FIG. 2   FIG. 3

FIG. 4   FIG. 5

FIG. 1 is a front elevational view of a dispensing tank showing my new design;

FIG. 2 is a side elevational view thereof showing the handle in its carrying position;

FIG. 3 is a rear elevational view thereof showing the handle in its non-carrying position;

FIG. 4 is a top view thereof; and

FIG. 5 is a bottom view thereof.

I claim:

The ornamental design for a dispensing tank for a floor treating machine or similar article, as shown and described.
